DESIGN FOR A WRINGER HEAD FOR WASHING MACHINES

Lurelle Van Arsdale Guild, Noroton, Conn., as-
signor to Montgomery Ward & Co., Incorpo-
rated, Chicago, Ill., a corporation of Illinois

Application May 16, 1933. Serial No. 48,129

Term of patent 7 years

To all whom it may concern:

Be it known that I, LURELLE VAN ARSDALE GUILD, a citizen of the United States, residing at Noroton, in the county of Fairfield and State of Connecticut, have invented a new, original, and ornamental Design for a Wringer Head for Washing Machines, of which the following is a specification; reference being had to the accompanying drawing, forming a part hereof.

In the drawing,
Fig. 1 is a side elevation of the wringer head for
washing machines showing my new design;
Fig. 2 is a plan view thereof; and
Fig. 3 is an end elevation of the same.

I claim:
The ornamental design for a wringer head for
washing machines, as shown.
